Primary Examiner — Gino Colan(74) *Attorney, Agent, or Firm* — Paul M. Denk(57) **CLAIM**

The ornamental design for a tilted poppet valve for fuel dispensing nozzle, as shown and described.

DESCRIPTION

FIG. 1 is an isometric view of a tilted poppet valve for fuel dispensing nozzle of showing our new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.
